C. L. SCHULZ.

HAIRPIN.

APPLICATION FILED OCT. 8, 1920.

Patented Oct. 24, 1922.

Inventor:
Charles Louis Schulz.
By Morsell + Keeney
Attorneys.

UNITED STATES PATENT OFFICE.

CHARLES LOUIS SCHULZ, OF MILWAUKEE, WISCONSIN.

HAIRPIN.

Application filed October 8, 1920. Serial No. 415,589.

To all whom it may concern:

Be it known that I, CHARLES LOUIS SCHULZ, a citizen of the United States, and resident of Milwaukee, in the county of Milwaukee, 5 and State of Wisconsin, have invented new and useful Improvements in Hairpins, of which the following is a description, reference being had to the accompanying drawings, which are a part of this specification.

10 This invention relates to certain new and useful improvements in hair pins.

Great difficulty is now experienced in the present construction of hair pins in that they are constantly slipping out and becoming lost and while the hair pins now in general use have been kinked or provided with irregularities in the sides thereof, still this fault has not been entirely eliminated.

15 Hence with the above and other objections in mind, this invention has for one of its objects to provide a hair pin which will remain in place until removed by the wearer.

Another object of this invention is to provide a hair pin formed from spring steel or other spring metal and having an intermediate restricted opening whereby the same must spring over the hair and offer resistance to the removal of the pin therefrom.

20 A further object of this invention is to provide a hair pin so designed as to offer six distinct shoulders or abutting faces to resist the removal of the pin from the hair.

A still further object of this invention is to provide a hair pin that may be produced 25 at the same cost of the hair pins now in general use and which will be practical for the purpose described.

With the above and other objects in view which will appear as the description proceeds, my invention resides in the novel construction, combination and arrangement of parts substantially as hereinafter described and more particularly defined by the appended claim, it being understood that such changes in the precise embodiment of the hereindisclosed invention may be made as come within the scope of the claim.

In the accompanying drawing, I have illustrated one complete example of the physical embodiment of my invention construct-

ed according to the best mode I have so far devised for the practical application of the principles thereof, and in which:

The single view illustrates a hair pin constructed in accordance with my invention. 55

Referring now more particularly to the accompanying drawing, my improved hair pin is formed from a single length of spring wire, or other suitable material 5 and has each side thereof formed with an outwardly 60 curved humped portion 6 spaced from the closed end or shank portion 7 of the pin, the lower portions of the humps 6 extending inwardly to a point slightly spaced from each other, as at 8, forming what may be termed 65 instruck portions. The sides are then struck or curved downwardly, as at 9, and then outwardly, as at 10, and then the sides continue parallel to form the legs 11 of the pin.

This construction forms an intermediate 70 restricted opening 12 through which the hair passes when the pin is inserted and which springs over the hair and confines a portion thereof in the space between the instruck portions 8 and the end 7 of the pin. When 75 the pin has been inserted in place, six abutments or shoulders, *a*, *b* and *c*, resist the detachment of the pin from the hair, as well as the restricted space 12 through which the hair, accumulated between the projections 80 8 and the end 7, must pass. The shoulders *b* form substantially complete closure means for the shank or closed end portion of the pin, the shoulders *b* being formed at substantially right angles to the axis of the pin. 85

By reason of the hair pin being made of spring or other material, the parts 8 may be sprung apart to engage or disengage the same with the hair and the same will immediately return to its normal position. 90

What I claim as my invention is:

As a new article of manufacture, a hair pin comprising a looped shank portion and a pair of tine portions, said pin intermediate the shank portion and said tine portions being formed with a pair of inwardly extending projections adapted to provide a substantially closed throat, the sides of said projections adjacent the shank portion being formed at substantially right angles to the 100

axis of the pin, those portions of the pin between the respective last mentioned sides of said projections and the sides of said shank portion being curved outwardly to form 5 rounded humps on the sides of the pin, and those portions of the pin between the respective sides of said throat and said tine por-

tions extending downwardly and then outwardly in the form of reverse curves to provide rounded shoulders on the sides of 10 the pin, for the purpose specified.

In testimony whereof, I affix my signature.

CHARLES LOUIS SCHULZ.
